No. 867,193.

PATENTED SEPT. 24, 1907.

E. FLANNIGAIN,
DENTAL SOLDERING APPARATUS,
APPLICATION FILED MAY 20, 1907.

UNITED STATES PATENT OFFICE.

EDWARD FLANNIGAIN, OF ST. LOUIS, MISSOURI, ASSIGNOR TO THE UNITED APPLIANCE MANUFACTURING COMPANY, OF ST. LOUIS, MISSOURI, A CORPORATION OF MISSOURI.

DENTAL SOLDERING APPARATUS.

No. 867,193.

Specification of Letters Patent.

Patented Sept. 24, 1907.

Application filed May 20, 1907. Serial No. 374,588.

To all whom it may concern:

Be it known that I, EDWARD FLANNIGAIN, a citizen of the United States, and a resident of the city of St. Louis and State of Missouri, have invented a new and 5 useful Improvement in Dental Soldering Apparatus, of which the following is a specification.

My invention relates to dental soldering appliances. It has for its principal object to facilitate the manipulation of the work so as to control the flow of the solder.

10 It consists principally in mounting the work and the heater therefor so as to be movable universally without changing their relative arrangement.

It also consists in the arrangements and combinations of parts hereinafter described and claimed.

15 In the accompanying drawing, which forms part of this specification, and wherein like symbols refer to like parts wherever they occur, Figure 1 is a vertical view, partly in section and partly in elevation, of my device with the cover in place; Fig. 2 is a vertical 20 view at right angles to the view of Fig. 1, with the cover removed and the cup shown in section, the burner being tilted at an angle; Fig. 3 is a detail perspective view of the shell of the combustion chamber and the support for the holder for the investment material; 25 Fig. 4 is a perspective view of a modification of the parts shown in Fig. 3; Fig. 5 is a perspective view of the investment material and the holder therefor; and, Fig. 6 is a perspective view of a modified form of such holder.

30 The base of my device comprises an ordinary tripod or pedestal 1. The upper end of this pedestal is split or slotted and a horizontal member 2 is swiveled or pivoted between the split portions to turn on a horizontal axis. In order that the horizontal member may 35 be easily turned and still have sufficient frictional engagement with its support to remain in any position to which it may be turned, an adjustable binding screw 3 extends through the split portions of the pedestal. At the end of the horizontal member is mounted 40 a soldering heater; and at the other end, said member is provided with a laterally projecting arm or hand lever 4 by which it may be turned to any desired position.

The soldering heater comprises a cup or hemispherical shell 5 through the lower part of which extends a gas pipe or the tube 6 of a Bunsen burner 7 which communicates through a tube 8 with any convenient source of gas supply. The end of the burner tube 6 terminates 45 in a combustion chamber which is formed by a hollow casting or shell 9. The bottom of said shell 9 has a circular opening which fits loosely over the end portion of the gas pipe or burner tube 6. The top of said shell is a plate 10 which has a multiplicity of holes 11 for the escape of the unconsumed gas as well as for the 50 products of combustion. By this arrangement, the

shell constituting the combustion chamber is swiveled on the end of the gas pipe or burner tube, so that it may be easily turned to any desired position thereon.

The top plate 10 of the combustion chamber is provided with supports adapted to receive and hold the 60 work to be heated. As shown in the drawing, said top plate is provided at diametrically opposite points with outwardly and upwardly extending arms 12 which are provided with upwardly extending pins 13. These pins are adapted to enter eyes or loops 14 formed 65 in metal bands 15 or other suitable holders for the investment material 16 surrounding the work 17 to be soldered. In order to prevent the investment material from becoming loose prematurely, it is desirable to perforate or roughen the band or holder in order 70 that such material may engage therewith. Preferably, also, such material is soluble in water so that it may be separated from the holder merely by immersion in water.

Obviously, the shell at the top of the burner tube 75 may be dispensed with or it may be fixed with respect to the burner tube. In either case, the arms 12 which support the holder for the investment material are fixed to a ring or collar 18 which swivels loosely on the burner tube, as illustrated in Fig. 4. Obviously, the 80 holder for the investment material may be made in a variety of ways.

As illustrated in Fig. 5 the holder is a mere band having laterally extending arms which are perforated 85 near their ends.

As illustrated in Fig. 6, the holder is a strip of metal bent into circular form at the middle and having lateral projections with eyes formed therein.

The operation of the device is as follows: The work to be soldered having been previously positioned in 90 the investment material, the holder 15 with such material therein is applied to the heater by fitting the eyes of the holder over the pins on the shell of the combustion chamber. A cover 19 is then placed on the hemispherical cup and the gas is then turned on 95 and ignited so as to heat and dry out the investment material. While the burner is still in operation, the cover is removed and the solder is applied to the work, and, preferably the flame of a blow pipe is impinged upon the particular portion of the solder that is being 100 worked so as to fuse the solder and make it flow easily. In the initial stage of the action, the position of the investment material is of little importance; but when the solder becomes fluid, it is necessary to control the direction of the flow thereof. For this purpose, the 10 hand lever on the horizontal member 2 is turned so as to tilt the soldering device to any desired angle, and from time to time this angle is varied to suit the requirements. The variation of the angle of the horizontal member determines the tilt or inclination of 11

the cup, but does not determine the direction of the solder flow. The direction of flow is determined by turning the shell on the burner tube so as to tilt the investment material in the desired direction. The 5 blow pipe itself furnishes a convenient instrument for turning the shell or the holder of the investment material. By this arrangement, the amount of inclination and the direction of inclination are both under the easy control of the operator.

10 Obviously, the device hereinbefore described admits of considerable variation without departing from my invention, and I do not wish to be restricted to the exact construction described.

15 What I claim as my invention and desire to secure by Letters Patent is:

1. A soldering apparatus comprising a burner swiveled on a horizontal axis and a work holder movable with the burner and swiveled with respect to the axis thereof.
2. A soldering apparatus comprising a pedestal, a member swiveled thereon on a horizontal axis, a burner supported by said horizontal member, a work holder above and movable with said burner and swiveled with respect thereto.
3. A soldering apparatus comprising a pedestal whose upper portion is split, a member swiveled therein on a horizontal axis, a screw for varying the friction of said horizontal member, and a work holder above and movable with said burner and swiveled with respect thereto.
4. A soldering apparatus comprising a pedestal, a horizontal member swiveled thereon on a horizontal axis, a work holder movable with the burner and swiveled with respect thereto, means for varying the frictional engagement of the horizontal member with the pedestal and a hand piece for turning said member.

5. A soldering apparatus comprising a pedestal, a member swiveled thereon on a horizontal axis, a cup mounted on said horizontal member, and a burner tube extending through said cup, a support swiveled on said tube, and a work holder on said support. 35

6. A soldering apparatus comprising a pedestal, a member swiveled thereon on a horizontal axis, a cup mounted on said horizontal member, a burner tube extending through said cup, a support swiveled on said tube, pins on said support and a work holder having eyes fitting over said pins. 40

7. A soldering apparatus comprising a pedestal, a horizontal member swiveled thereon, a cup mounted on said horizontal member, a burner tube extending through said cup, a shell swiveled on said tube and constituting a combustion chamber for said burner, laterally extending arms 50 on said shell, and a work holder on said arms.

8. A soldering apparatus comprising a pedestal, a horizontal member swiveled thereon, a cup mounted on said horizontal member, a burner tube extending through said cup, a shell swiveled on said tube and constituting a combustion chamber for said burner, laterally extending arms 55 on said shell, a work holder on said arms, and means for turning said horizontal member.

9. A soldering apparatus comprising a pedestal, a horizontal member swiveled thereon, a cup mounted on said horizontal member, a burner tube extending through said cup, a shell swiveled on said tube and constituting a combustion chamber for said burner, laterally extending arms 60 on said shell, a work holder on said arms, means for turning said horizontal member, and means for varying its frictional contact with the pedestal.

Signed at St. Louis, Missouri, this 17th day of May, 1907.

EDWARD FLANNIGAIN.
